UNITED STATES PATENT OFFICE.

JOHN J. ZEITZ, OF WARREN, OHIO, ASSIGNOR TO THE AMERICAN FOLDING MACHINE COMPANY, OF WARREN, OHIO, A CORPORATION OF OHIO.

STACKING MECHANISM IN PAPER-FOLDING MACHINES.

1,188,365.

Specification of Letters Patent. Patented June 20, 1916.

Application filed December 19, 1913. Serial No. 807,583.

To all whom it may concern:

Be it known that I, JOHN J. ZEITZ, citizen of the United States, residing at Warren, in the county of Trumbull and State of Ohio, have invented certain new and useful Improvements in Stacking Mechanism in Paper-Folding Machines, of which the following is a specification.

This invention appertains to a stacking mechanism for paper folding machines, and is an improvement adapted more especially to be used with a folding machine invented by Albert D. Pejano and John J. Zeitz, and patented June 9, 1914, No. 1,099,884.

In the accompanying drawings, Figure 1 is a rear elevation of the machine showing the stacking mechanism at the middle of the machine with a directly downward feed. Fig. 2 is a horizontal view on a sectional line just above the stacking table and showing the said table adjusted to the right of the machine and with the folding head and its rollers in a vertical position to deliver at its side. Fig. 3 is a side elevation of the machine showing the reverse side from Fig. 4. Fig. 4 is a vertical sectional elevation on the axis of the folder head and corresponding substantially to line 4—4, Fig. 2. Fig. 5 is a sectional plan view of the machine. Fig. 6 is a sectional view of a detail herein-after more fully described.

The present invention being limited to the stacking portion of the machine herein shown the description which follows will be correspondingly confined to the stacker alone except as may be necessary to make the entire operation intelligible. Furthermore, it will be understood that stackers, as such, in connection with paper folding machines are not at this time a broadly new conception and a form thereof is shown in the above named application, but the particular stacking mechanism contained herein is believed to be entirely new and patentable and has been found both simple and effective for doing the work. To these ends the said mechanism comprises a stacking table *a* upon which the folded sheets are delivered from between the last two rollers *r* of the series of feed rollers shown, and are received on said table so rapidly that the passage of the paper from the rolls to the table is difficult to follow with the eye, and such delivery is edgewise upon said table

next in advance of the stop or head *h* 55 against which the stack is pressed by the stacker and is further held as hereinafter described. The said head or stop *h* is a fairly heavy piece of cast metal, preferably, and slidable in a slot in the table, the weight 60 however, being such that it can be pushed back by the positive pressure of the stacker *a* as the stack accumulates before it on the table. When the said stop reaches the rear end of the table the machine is momentarily 65 stopped to remove the sheets, when operations are again resumed after sliding the said stop inward to the starting point.

The stacker *s*, so called, or part which carries the sheets forward successively as they 70 come through the rolls *r* to or against the stop *h*, is adapted to have a back and forth or to and fro travel within limits, say three to four inches, and is located directly opposite said head above the surface of table 75 *a* and slides in an open slot in the end of the table *a*, or rather the said stacker is vertically adjustable by check *c* engaging the stem 2 through a head *d* which carries the stacker and travels back and forth in said 80 slot in the table.

Actuation of the stacker proceeds primarily from a cam *c* mounted on a shaft 3 at the rear of the machine and is supported relatively beneath or from the table *a* by means of a suitable bracket *b*. The said cam is preferably of disk shape and has a cam groove or channel 4 in the side thereof in which a roller or wheel 5 on lever 6 is 85 operatively engaged. The said lever is pivoted at its lower end in the bracket or hanger *b* fixed in the bottom of table *a* and has said roller 5 near its middle while the stacker actuating link connections 8 engage the upper end of said lever and proceed 90 thence to stacker supporting head *d* through a sleeve or other suitable support *k* on the bottom of the table. The cam *c* thus governs the throw of the stacker and by said 95 cam the to and fro movements thereof are 100 made positive within fixed limits.

The cam shaft 3 is parallel to shaft 9, and idler shaft 10 intervenes and a train of gears, *g*, *g'* and *g''* communicate power from shaft 9 to shaft 3. The said shaft 9 may be 105 connected up with the driving power of the machine by any suitable means, such, for example, as by the depending shaft 12, Fig.

1, and bevel gears 13 at the junction thereof with shaft 9, or by any other suitable train of power connections.

The table *a* is both vertically and laterally adjustable according to the work to be done, and may be positioned at the middle of the machine as seen in Fig. 1, or at the side as seen in Fig. 2, and is slidable laterally in or upon the cross frame or bar 14 beneath and locked here or there by bolt *b'*, Fig. 4. The said cross support 14 extends between the two vertically disposed channel iron posts or standards 15 of the main frame of the machine and the adjusting screws 16 are in relation to engage in sleeve nuts in the ends of the said cross-bar or frame and serve to fix the elevation thereof. The said screws are themselves jointly controlled by a transversely disposed shaft 20 carrying bevel or miter gears 21 meshing with similar gears 22 on the respective screws 16, and adapted to turn the same to effect the up and down movements of the said table support 14 and the parts carried thereby as the different kinds of work may require, the folds being of varying depth or width and requiring correspondingly different elevations of table *a*.

The elevation of a table *a* being determined through the foregoing mechanism the folded stock is delivered thereon and stacked against the stop or block *h* as hereinbefore described and held when the stacker retires by the spring pressed fingers *f* in the said table. These fingers are pivoted to allow the paper to be pushed over them by the stacker in its forward movement but under spring pressure they instantly assume the upright position shown in Fig. 4 when the stacker retires and hold sheets in stacked position. As a matter of practice the stop *h* is up fairly close to the outer set of fingers when the stacking begins, and it is gradually pushed back as the size of the stack increases, until at last the said stop is carried gradually to the rear of the table where a bell may be placed to be rung by contact by the stop to tell that the table is full. As the stack increases in size it covers the outer set of fingers and the inner set come into action.

A pair of side arms *m* have sheet spring or equivalent fingers or projections *n* in their ends which coöperate with the fingers *f* in sustaining the folded stock on the table, and said arms serve also as means for alining or confining the stock within limits at the ends thereof. The said arms are vertically adjustable in right angled brackets 25, and said brackets are laterally adjustable in slot 26 beneath and extend laterally in respect to the table.

It should be understood that the rotatable head 30 which carries the feed rollers *r* is 65 rotatable on its axis 31 so as to feed the

folded stock directly downward, as in Fig. 1, and to a quarter turn around to feed laterally, as in Fig. 2. However, the means whereby the feeding is accomplished belongs to the application above identified and is only incidentally present herein and rotatable as two or more folds in the paper are desired.

From the foregoing it will be seen that the stacking table carries all the stacking mechanism, and the shaft 9 is splined so that gear *g* thereon may slide to accommodate the movements of the table to center or side of the machine, and actuate the cam *c* whether in one position or the other. The present invention therefore has only one packing table, slidably mounted on bar or rail 14 and can be located to do its work in any position from one end of said rail to the other. When located at either extreme for right angle work, and when in the middle for parallel work, the packing table and rail are raised and lowered with a screw, making it convenient for the operator to adjust it for height, etc.

The stacker or jogger *s* is positively actuated back and forth by a slot cam, eliminating a spring return and unnecessary friction and work, thereby greatly increasing the life of same, and making it durable and practical. This also is a desirable feature in that it prevents a delivered sheet from interfering with the next one by pushing the already delivered sheet completely out of the way behind the floppers *n* in the side retaining arms *m* and floppers or fingers *f* in bed of frame. All the mechanism for actuating the jogger is contained and fastened to frame 14 except the rotating means, such as shafts and beveled gears.

What I claim is:

1. A stacking mechanism for paper folding machines having a stacking table adjustable vertically and laterally, a stacker at the inner end of said table, a cam wheel mounted on said table and an operating lever engaged therewith, and links connecting said lever with said stacker and adapted to reciprocate the same over said table.

2. A paper folding machine and a single stacking table vertically and laterally adjustable, in combination with stacking means mounted upon said table and adjustable therewith, said means comprising a sliding stop for the folded product, pivoted fingers in said table in advance of said stop, an arm at each side of said table and relatively above the same and a reciprocating stacker.

3. A stacking mechanism for paper folding machines comprising a single stacking table and operating mechanism carried thereon to stack the folded papers, a bot-

tom support and means for adjusting the table and operating mechanism laterally on said support thereby setting the table to the center or to the side of the machine 5 as shall be needed and means for driving said operating mechanism.

4. The stacking mechanism described comprising a stacking table and reciprocable stacking means carried thereon, a bot-
10 tom support and means between said parts by which the said table and stacking means are laterally adjustable, in combination with mechanism at both sides of the machine

to raise and lower said support according to the elevation desired for the said table, and vertical and horizontal driving shafts having slideable gear connections and the said reciprocable stacking means having slideable driving connection with said horizontal shaft. 15

In testimony whereof I affix my signature in presence of two witnesses.

JOHN J. ZEITZ.
